Filed Sept. 27, 1960, Ser. No. 62,280

Term of patent 14 years

(Cl. D13—1)

Fig. 4

Fig. 5

Fig. 6

Fig. 1 is a front perspective view of a house embodying my new design;

Fig. 2 is a front elevational view of the house;

Fig. 3 is an enlarged fragmentary perspective view of the front entrance portion;

Fig. 4 is a rear elevational view;

Fig. 5 is a right side elevational view;

Fig. 6 is a left side elevational view; and

Fig. 7 is a top plan view.

For convenience of illustration only parts of the brick and stone side surfaces and the shingle roof have been shaded in the several views on the drawing. It is to be understood that these surfaces continue throughout the plain areas shown.

The design of this invention is dominated by the front design of the house, and particularly the front entrance portion thereof, as illustrated most clearly in Figs. 1, 2 and 3.

I claim:

The ornamental design for a house, as shown and described.
